United States Patent Office.

HENRY HOFFMAN, OF JENNER'S X-ROADS, PENNSYLVANIA.

Design No. 2,713, dated July 30, 1867.

DESIGN FOR A COFFIN.

The Schedule referred to in these Letters Patent and making part of the same.

TO ALL WHOM IT MAY CONCERN:

Be it known that I, HENRY HOFFMAN, of Jenner's X-Roads, in the county of Somerset, and State of Pennsylvania, have invented a Design for a Coffin; and I do hereby declare that the following is a full, clear, and exact description thereof, reference being had to the accompanying drawings, making part of this specification, and to the letters of reference marked thereon.

Like letters indicate like parts wherever they occur.

To enable others skilled in the art to construct and use my invention, I will proceed to describe it.

To construct a coffin after my improved design, I take any suitable material and so cut and unite the parts as to form a coffin of the form represented in perspective in Figure 1, the sides, both above and below, being inclined as represented, and a ledge or rim, C, being formed around the edges where the upper and lower portions are united, as represented. An opening is cut in the cover and a plate of glass inserted, as shown at α of Figure 2, a piece, B, being provided to shut over and cover the same, as represented. The coffin may be formed either of wood or metal, the form in either case being the same.

Having thus described my invention, what I claim, is—

The within-described design for a coffin made as herein shown.

HENRY HOFFMAN.
